UNITED STATES PATENT OFFICE.

VERNOR ALDER, OF AUBURN, VICTORIA, AUSTRALIA.

AIR-ADMISSION-CONTROL DEVICE FOR INTERNAL-COMBUSTION ENGINES ON MOTOR-DRIVEN VEHICLES.

Application filed March 9, 1926, Serial No. 93,457, and in Australia March 18, 1925.

The present invention refers to devices for controlling air admission to the cylinders of an internal combustion engine constituting the power unit in a motor driven vehicle and has been devised to provide a device for that purpose which while capable of effectively performing the functions of existing devices is also adapted to prevent unauthorized starting of the engine.

10 Briefly stated the essential feature of the invention resides in a valvular arrangement controlling admission of air to the engine cylinders, wherein the valve setting can be locked in such a position that the carburetted mixture is so diluted with air that it is incapable of being ignited.

In one practical form of such a valvular arrangement the valve mechanism comprises a pair of rotary valves each separately operable to control one of a pair of air ports and both of which valves must be brought into a predetermined registration to close both ports before the engine can be started. The setting of such registration can conveniently be controlled by a pair of aligned discs bearing a circumferential series of numerals, letters or markings, which must be brought into a predetermined order before the setting mentioned can be effected. Each of said 25 discs controls the operation of one of said valves, as by means of an extended spindle on each of the latter to which spindles said discs are secured.

30 The accompanying drawings illustrate a practical application of the invention.

In these drawings, Fig. 1 is a side elevation of a practical form of the device shown fitted on the instrument board of a motor driven vehicle.

40 Fig. 2 is an enlarged vertical longitudinal central section of the device and Figs. 3 and 4 are transverse sections on lines III—III and IV—IV respectively in Fig. 2.

The valve casing 5 and associated air chamber 6 are in communication through ports 7 and 9 controlled by the rotary valves 8 and 10 respectively.

45 The air chamber 6 is placed in communication with the inlet manifold 11 (shown in dotted lines in Fig. 1) by any suitable conductor as for example the flexible tube 12 having a terminal union and fitting 13 of

any suitable type and the uncoupling of which latter from its union may be guarded against by welding or soldering.

55

Each of the rotary valves 8 and 10 is made up of a pair of apertured discs 14 having a common boss 15 the bridging portion 16 between said discs having an area sufficient to completely cover the ports 7 and 9 and for fine adjustment of the passage of air to said ports the transverse edges 17 of said portion 16 converge as shown. The boss 15 of the valve 8 is stepped as shown in Fig. 2, and is integral with the hollow spindle 18 while the boss of the valve 10 is integral with the spindle 19 which passes through said hollow spindle 18 and extends beyond the outer end of the latter. An enlarged cylindrical portion 20 is formed on the spindle 19 to act as a bearing support for the rotary valve 8 and the rear end of the said spindle 19 enters a bearing recess in the rear end 21 of the valve casing 5, which end is slotted at 22 for the passage of air into the casing 5. The forward end of the casing 5 is fitted with an apertured cap member 23 having an internally threaded boss 24 and inwardly projecting flange 25 acting as a bearing support for the forward cylindrical portion of the boss 15 of the rotary valve 8.

65

70 Into the boss 24 of said cap 23 is screwed the hollow stem 26 of a disc 27 centrally apertured for the free passage there-through of the hollow spindle 18 of the rotary valve 8. A washer 28 and a clamping nut 29 on the stem 26 are provided for securing the device to the instrument board 30.

75

75 Discs 31 and 32 are respectively attached to the spindles 19 and 18 respectively of the valves 10 and 8 respectively, said discs being retained against longitudinal movement by the screw 33. The discs 31 and 32 are employed for imparting rotary motion to the valves 10 and 8, and are preferably attached to the spindles by keys 34 (see Fig. 3) which engage any diametrically opposite pair of the longitudinally disposed recesses 35 in said spindles.

80

85 The discs 31 and 32 are provided with a peripheral series of numerals as shown in Fig. 3 or other markings, as may also the periphery of the disc 27 which latter is not

however essential, it being necessary for engine starting purposes to set certain of the numbers parallel with the axis of the spindles 18 and 19, in a predetermined alignment—determined according to the positions of the valve bridging portions 16 and the ports 7 and 9 when covering the latter—and also in alignment with a fixed marking as for instance one of the numbers on the 10 fixed disc 27. The ports 7 and 9 being covered against admission of air to the air chamber 6 and the engine running, one or other of the valves 8 and 10 can be adjusted to provide any slight additional air considered necessary for more efficient running of the engine while the remaining valve can be used at any time required for engine braking purposes which latter can if necessary be increased to its full extent by opening up both of the valves to the fullest extent. As previously stated the valve controlling discs 31 and 32 are preferably secured to their respective valve spindles by the keys 34 engaging recesses 35 in the latter the plurality of said recesses being provided so that the numbers on said discs which require to be aligned for engine starting purposes can be varied at any time.

With the arrangement described the device is adapted, in addition to the functions of admitting limited quantities of extra air to the combustible fuel mixture and large quantities for engine braking purposes, for use in preventing the engine being started 35 by any unauthorized person unacquainted with the "key" position of the discs 31 and 32.

It is of course evident that more than two of the valves 8 and 10 can be used with an additional disc for operating each further 40 valve and a predetermined setting required of all of the same for engine starting purposes.

In addition further discs such as 27 can be incorporated which may or may not be fixed, 45 for the purpose of confusing any unauthorized person observing the operation of setting the discs in the required relationship for starting the engine.

I claim:

An air admission control device for internal combustion engines comprising a valve chamber communicating with the atmosphere, a plurality of air ports in the chamber casing leading into the engine manifold, a plurality of axial aligned rotary air valves of cylindrical form in the valve chamber and spaced from each other in an axial direction, the rotary air valves being each formed of a pair of axially aligned 60 discs having a common boss and a bridging portion between said discs of sufficient area to cover completely the respective air port, and spindles for the respective valves extending outside the valve chamber and having at their outer ends circumferentially marked permutation discs for moving the spindles and the valves attached thereto into various relative predetermined positions for regulating the quantity of air admitted by 65 the said ports.

Dated this eighth day of February, 1926.

VERNOR ALDER.
